CIRCUMCISION INSTRUMENT

Morris Hyatt, Philadelphia, Pa.

Application October 10, 1947, Serial No. 779,066

4 Claims. (Cl. 128—305)

1

My invention relates to a surgical instrument used in the surgical operation known as circumcision, which consists in removing a portion of the prepuce, thereby exposing the glans penis.

Heretofore, other circumcision instruments have been made in many different sizes, ranging from infant size where the glans diameter is approximately 1.1 cm. ($\frac{7}{16}$ "), to adult size where the glans diameter is approximately 3.5 cm. ($1\frac{3}{8}"). The complete set of instruments represents a considerable investment for the average physician.$

It is an object of my invention to provide a circumcision instrument having a removable cone and base plate whereby a kit of different sizes of cones and complementary base plates may be used with the one instrument.

Another object of my invention is to provide a circumcision instrument by means of which the entire operation may be performed without the aid of an assistant and in much less time than in any other existing method or instrument.

Another object of my invention is to provide a rapid means for tensioning the prepuce about the cone so that the surgeon may use his scalpel with certainty and accuracy.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawing in which:

Fig. 1 is a plan view of a circumcision instrument embodying my invention.

Fig. 2 is a side view of the instrument illustrated in Fig. 1 showing in dotted lines how the cone holder may be shifted.

Fig. 3 is a bottom view of my circumcision instrument.

Fig. 4 is an end view taken along the line 4—4 of Fig. 1.

Fig. 5 is a fragmentary top view, in open position, of the base plate.

Fig. 6 is a fragmentary bottom view, in open position, of the base plate jaws.

Fig. 7 is a top view of the cone holder, the cone and base plate, the clamping nut having been removed.

Fig. 8 is a sectional view taken along the line 8—8 of Fig. 4.

Fig. 9 is a sectional view taken along the line 9—9 of Fig. 4.

Referring now to the drawing, wherein similar reference characters designate similar parts, I show an instrument for performing circumcision

2

safely and easily, and which reduces to a minimum the possibility of infection or hemorrhage. The circumcision is practically bloodless and in the very few cases where bleeding occurs, it is so slight that no suture nor even ligation is necessary.

The handle A of the instrument comprises two similar members 10 and 12, which members are joined together on a sliding pivot 14. The handle members also have projections 13 and 15, whose laterally abutting surfaces are ridged, so that the handles may be locked at any degree of closure, in the manner of a hemostat.

Pivoted to the handle members 10 and 12 are a pair of complementary jaws 16 and 18, which are pivoted together at 20. The free ends 22, 24 of the jaws 16, 18 are semi-circular, and when abutting one another, as in Fig. 3, they form an annular base plate, designated as B. Jaw 18 has a tit 19 which cooperates with a depression 17 in jaw 16 to align the closure. The base plate B is inwardly hollowed on its lower surface, as at 26. A link C has one end fastened to the pivot 20 and has at its other end an elongated slot 28, within which the pivot 14 slides as the handle members are moved together or apart.

It can be seen that as the handles 10 and 12 are moved together, the jaw ends 22 and 24 also move together, and vice versa.

Supported upon link C is a bracket D, hinged to the link at 27. The free end 29 of the bracket D is forked to admit the threaded end 32 of the clamping screw 30. The clamping screw 30 has an externally threaded end 32, an internally threaded end 34, and a shoulder 36 formed integrally with the screw at the base of the threaded end 32.

A penis-receiving cone or bell, designated generally as E, has a stem end 38 adapted to thread into the end 34 of the clamping screw 30, and has a cone portion 40 which is embraced by the semi-circular jaws of the base plate B, and the cone also has a cylindrical portion 42.

The hinged bracket D is adapted to swing from its inoperative position, shown in phantom outline in Fig. 2, to its operative position, as shown in solid lines in the same figure. A thumb nut 44 operates upon the portion of the threaded end 32 which protrudes through the bracket D so that as the thumb nut is tightened, the cone is drawn into the annular base-plate D.

In order to stretch and grasp the prepuce to a position where it is held, I provide a tension carriage, generally designated as F, illustrated in Fig. 9 which is adapted to slide along the outside of the stem of clamping screw 30. The tension carriage F consists of a plate 50 which encircles and is adapted to slide along the unthreaded portion of the clamping screw 30. Accordingly, the plate may be manually posi-

tioned at any point on the unthreaded length of the screw. The ends of the plate are bifurcated to receive a pair of clips 52 which are urged by coil springs 54 so that their arcuate ends 56 bear against the cylindrical portion of the cone E when the instrument is not in use but the clips stretch and grasp the prepuce when an operation is being performed. The arcuate ends 56 of the clips may be spread apart by compressing the finger ends 58.

In performing a circumcision, my instrument is used as follows:

With the patient upon the operating table, a cone E of the proper size for the glans penis (this may be determined by trial) is selected from the kit and assembled to the instrument. The thumb nut 44 is backed off, and the jaws of plate B are spread apart. The cone is lubricated with vaseline and slipped over the glans penis within the prepuce, so that the free end of the frenum is on a level with the rim of the cone. The prepuce is then grasped by the spring clips 52 and stretched by moving the carriage F back. The jaws 16, 18 of the plate B are then closed and locked using the ridged projections 13, 15 of the handle for this purpose. The thumb screw 44 is turned until the cone portion 40 is drawn in firmly against the plate B.

At this point, the cone E completely covers the glans penis, and that portion of the prepuce which is to be removed is stretched about the cylindrical portion 42 of the cone on the upper side of plate B. The instrument is left in position for about 5 minutes, during which time the pressure of the cone against the plate produces hemostasis or stoppage of the blood vessels in the annular region of the prepuce which is to be cut. It is now a relatively simple matter for the surgeon to pass his scalpel around the cylindrical portion 42 of the cone E, close to the plate B, and remove the redundant tissue. The operation is now complete, and the instrument is released by backing off the thumb nut.

Since the cone E and the plate B are of one definite size, I provide in the kit a number of cones to cover the entire range of sizes previously described, together with the corresponding plates B. As shown in Fig. 8, the cones E are easily interchanged by screwing them into the end of clamping screw 30. Likewise, the jaws which form plate B are interchangeable, by removing the pivots at 21.

Although my invention has been described in considerable detail, such description is intended as being illustrative rather than limiting, since the invention may be variously embodied, and the scope of the invention is to be determined as claimed.

I claim as my invention:

1. A circumcision instrument comprising a pivotally mounted two-piece base portion wherein

one end of said base portion forms a ring-like member, a penis-receiving bell adapted to pass through said ring-like member, means to adjustably clamp said bell in said ring-like member, and means mounted upon said first named means to stretch and to grasp the prepuce and to hold it in its proper position.

2. A circumcision instrument comprising a pivotally mounted complementary two-piece base portion wherein one end of said base portion forms a ring-like member, a penis-receiving-bell adapted to pass through said ring-like member, and means to adjustably clamp said bell in said ring-like member, comprising a removable threaded extension having a flange thereon attached to said bell, a nut on said extension, and a pivoted bracket to which extension is held.

3. A circumcision instrument comprising a pivotally mounted complementary two-piece base portion wherein one end of said base portion forms a ring-like member, a penis-receiving-bell adapted to pass through said ring-like member, means to adjustably clamp said bell in said ring-like member, and a pivoted two-piece handle which is pivotally attached to said two-piece base portion whereby said handle may open and close said ring-like member.

4. A circumcision instrument comprising a pivotally mounted complementary two-piece base portion wherein one end of said base portion forms a ring-like member, a penis-receiving-bell adapted to pass through said ring-like member, means to adjustably clamp said bell in said ring-like member, a bracket adapted to support said means, a link to which said bracket is pivotally connected, said link having a slot therein, a pivot, a pair of handles connected to said two-piece base portion, said pivot passing through said link slot and said handles, and a nut to lock said link and said handles in rigid position, to prevent movement of said two-piece base portion.

MORRIS HYATT.
